UNITED STATES PATENT OFFICE.

JAMES M. WALSH, OF MILWAUKEE, WISCONSIN, ASSIGNOR TO JAMES M. WALSH CO.,
OF MILWAUKEE, WISCONSIN, A CORPORATION OF DELAWARE.

SNAP HOOK.

Application filed June 27, 1925. Serial No. 40,021.

This invention relates to improvements in snap hooks more particularly adapted for use with harness.

In the ordinary snap hook the locking member is yieldingly held in locked position by a spring and when the spring breaks the hook is usually thrown away as worthless. Other forms of snap hooks have separable locking members which may be removed to replace the spring if broken, but if easily removable the locking member is apt to accidentally separate from the hook, and the parts become lost.

It is one of the objects of the present invention to overcome the before mentioned objectionable features and provide a snap hook with a non-removable locking member which is yieldingly held in locked position by a replaceable spring.

20 A further object of the invention is to provide a snap hook in which the locking member hook may be easily replaced if broken without removing the locking member from the hook.

25 A further object of the invention is to provide a snap hook having means for preventing the strap stitching from running off the side edges of the strap to which the hook is attached and also to hold the hook in aligned position with the strap.

30 A further object of the invention is to provide a snap hook which is of simple construction, is strong and durable, and is well adapted for the purpose described.

35 With the above and other objects in view, the invention consists of the improved snap hook and its parts and combinations as set forth in the claims, and all equivalents thereof.

40 In the accompanying drawing in which the same reference character indicate the same parts in all of the views:

Fig. 1 is a side view of the improved snap hook, the view also indicating by dotted lines the manner of attaching a strap thereto;

Fig. 2 is an edge view thereof; and

Fig. 3 is a side view of the snap hook, the locking member or keeper being shown in section.

45 Referring to the drawing, the numeral 5 indicates the body of the improved snap hook which is provided with a shank 6 having a hook 7 at one end. The opposite end 55 of the body is provided with an eye 8 hav-

ing a straight strap engaging portion 9 and strap sewing recesses or slots 10 formed by the projecting fingers 11. These fingers are adapted to extend between the loop of the strap 12 and the fingers 11 to prevent the 60 lines of sewing 13 from running off the opposite side edges of the strap 14 in sewing. Said fingers also hold the hook in alignment with the strap.

A locking member or keeper 14 of U- 65 shape in cross section is formed with opposite side pivot ears 15 and opposite side guard projections 16. The ears 15 straddle the body portion and are pivotally connected thereto by a pivot pin 17 while the 70 projections 16 slidably extend on opposite sides of the shank portion 6 to maintain the part engaged by the hook in its proper place. The end portion 14' of the keeper extends 75 inside of and overlaps the end portion 7' of the hook 7.

The side edge portion of the body 5 between the ears 15 is formed with a curved recess 18 forming retaining shoulders 19 and 20. A U-shaped spring 21 having stem 80 portions 21' of substantially equal length is positioned between the shank 6 and the keeper 14 and extends into the curved recess 18 of the shank between the shoulders 19 and 20 thereof. As thus positioned, the shoulders and the opposite side portions of the keeper 15 maintain the spring yieldingly in position but permit the easy replacement of the spring, when necessary. The spring will yieldingly hold the keeper against the 85 point of the hook, and in the event it is damaged or broken, it can be pushed outwardly toward the hook and be removed, and a new spring can be easily pushed into position from the eye of the hook. 90

95 From the foregoing description, it will be seen that the snap hook is of very simple construction and is well adapted for the purpose described, and in the event of the weakening or breaking of the spring, the spring 100 may be easily replaced without removing the hook from the harness to which it is attached.

What I claim as my invention is:

1. A snap hook, comprising a member 105 having a body portion and a shank with a hook formed at its end, a keeper member formed with eyed ears and guard projections which extend on each side of the member, means pivotally connecting the eyed 110

ears to the body portion, one of the two members having a recess forming shoulders adjacent the other member, and a U-shaped spring removably positioned between the 5 eyed ears and between and engaging the two members and entering the recess between the shoulders.

2. A snap hook, comprising a member having a body portion provided with a side edge recess forming shoulders and also having a shank with a hook formed at its end, a keeper member having opposite side eyed ears and opposite side guard projections which extend on each side of the body portion, means pivotally connecting the eyed ears to the body portion, and a U-shaped spring removably positioned between the eyed ears and between the two members and having one of its stem portions extending 10 into the body portion recess between the shoulders and removable in a direction toward the hook.

3. A snap hook, comprising a member having a body portion provided with a side edge recess forming shoulders and also having a shank with a hook formed at its end, the body portion also having an eye and fingers projecting from the eyed portion to form sewing slots, a keeper member having 25 opposite side eyed ears and opposite side guard projections which extend on each side of the body portion, a pin extending through the eyed ears and the body portion to pivotally connect the keeper member thereto, and 30 a U-shaped spring having stems of equal

length removably positioned between the two members and between the eyed ears and having one of its stem portions extending into the recess and between the shoulders while the other stem portion bears against the inner side of the keeper member between side portions thereof, said spring being removable in a direction toward the hook. 40

4. A snap hook, comprising a member having a body portion provided with a side edge curved recess forming shoulders and also having a shank with a hook formed at its end, the body portion also having an eye and fingers projecting from the eyed portion to form parallel sewing slots, a keeper member having opposite side eyed ears and opposite side guard projections which extend on each side of the body portion, the outer end portion of the keeper member engaging the 45 end of the hook in overlapping relation, a pin extending through the eyed ears and the body portion to pivotally connect the keeper member thereto, and a U-shaped spring removably positioned between the two members and between the eyed ears and having 50 one of its stem portions extending into the recess and engaging the shoulders while the other stem portion bears against the inner side of the keeper between side portions thereof, said spring having its stem extending toward the hook and the spring being removable in a direction toward the hook. 55

In testimony whereof, I affix my signature.

JAMES M. WALSH.
